UNITED STATES PATENT OFFICE.

GEORGE M. EATON, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,321,513.

Specification of Letters Patent. Patented Nov. 11, 1919.

Application filed April 4, 1914, Serial No. 829,432. Renewed April 12, 1919. Serial No. 289,743.

To all whom it may concern:

Be it known that I, GEORGE M. EATON, a citizen of the United States, and a resident of Pittsburgh, in the county of Allegheny and State of Pennsylvania, have invented a new and useful Improvement in Control Apparatus, of which the following is a specification.

My invention relates to control apparatus for governing the operation of dynamo-electric machines, and it has special reference to liquid rheostats which are adapted for use in connection with alternating current induction motors.

One of the objects of my invention is to provide a simple and inexpensive device of the above indicated character which shall be light in weight and compact in structure, and shall embody an improved, effective and reliable means for fixing the level of the electrolyte contained within the rheostat tank and for governing the discharge of the electrolyte therefrom.

It is the special object of my invention to improve the construction and operation of a combined discharge and regulating valve for liquid rheostats, such as is set forth in detail in a co-pending application, Serial No. 829,419, filed April 4, 1914, by Karl A. Simon, and assigned to the Westinghouse Electric & Manufacturing Company.

According to my invention, I provide a liquid rheostat having a bottom discharge opening with which a plurality of relatively movable coöperating tubular members are associated to constitute a telescopic valve, for the purpose of fixing the electrolyte level and for opening and closing the discharge opening.

In the accompanying drawing, Figure 1 is a view, partially in section and partially in side elevation, of a rheostat constructed in accordance with my invention, and Fig. 2 is a sectional view of the telescopic valve shown in Fig. 1, the section being taken along the line II—II of that figure.

Referring to the drawing, the apparatus shown comprises a tank 1 adapted to contain a suitable electrolyte, a plurality of sets of coöperating electrodes 2, an inlet port 3 and a telescopic valve 4.

The tank 1 may be of any suitable construction, although it preferably has its lowered portion tapered and provided with an

opening 6 through which electrolyte may be discharged.

Since the electrodes 2 form no material part of my invention, they may, of course, be of any construction known to the art. Moreover, the number of sets of electrodes is not essential, as my invention is applicable to rheostats adapted for either single-phase, polyphase or direct-current energy.

The telescopic valve 4 is compound in structure and function, and embodies a stationary tubular member 9 which is preferably secured to the inner edge of the tank opening 6 and which projects upwardly into the rheostat to a height slightly above the lower ends of the electrodes 2. The stationary member 9 is provided near its lower end, and just above the opening 6, with a plurality of apertures 10 of liberal size. If desired, the stationary tubular member 9 may be disposed entirely above the opening 6 and be supported in position by separate members which correspond to the integral portions 11 between the several apertures 10, although the specific form illustrated is probably to be preferred.

Surrounding the lower end of the tubular member 9 is a relatively movable tubular member 12 which is adapted to rest upon a seat 13 in the lower portion of the tank 1 and to cover and close the apertures 10 of the stationary member 9. The movable member 12 is attached, by means of members 14, to supporting yoke 15 which is carried in turn by a rod 16. The rod 16 projects through a suitable opening in a cover 17 and is adapted to be actuated by any suitable apparatus (not shown), such, for instance, as an electro-pneumatic power device or the like.

A third tubular member 20 is disposed within the upper portion of the stationary member 9 and is adapted to be raised and lowered by means of any suitable operating mechanism or apparatus through the agency of a supporting yoke 21 and a rod 22 which projects through the cover 17.

Assuming the parts of the apparatus to occupy the positions shown, the operation thereof is as follows: The inlet port 3 is first opened to allow the admission of electrolyte, which quickly fills the lower tapered portion of the rheostat tank 1 and makes contact with the lower ends of the electrodes

2. The height to which the electrolyte is raised is determined by the height of the movable tubular member 20, and, the excess of electrolyte overflows into the valve 4 and is discharged through the opening 6. If the tubular member 20 is gradually raised while the electrolyte is being admitted into the rheostat, the level thereof is correspondingly raised and, of course, determined, at 10 all times, by the height of the member 20.

Whenever it is desired to empty the rheostat tank 1, the tubular member 12 is raised to uncover the apertures 10 through 15 which the electrolyte flows in a lateral direction and is discharged through the opening 6.

Obviously, my invention is not restricted to the specific structural details herein set forth; as it will be understood that the member 12 which governs the discharge may be located within the stationary member 9, while the member 20, which fixes the electrolyte level, may equally well be disposed outside of the stationary member 9. Other 25 modifications may also be made without departing from the spirit and scope of my invention and I desire that only such limitations shall be imposed as are indicated in the appended claims.

30 I claim as my invention:

1. The combination with a liquid-containing tank having a discharge opening, of a stationary tubular member and a plurality of vertically movable tubular members respectively disposed within and without said stationary member and coöperating with the opposite ends thereof for respectively fixing the height of the liquid and controlling the discharge of liquid through said 40 opening.

2. The combination with a liquid-containing tank having a discharge opening, of a stationary hollow member, and a plurality of coöperating hollow members located on 45 opposite sides of said stationary member and movable in the same directions for separately governing the discharge of liquid

through said opening and fixing the height of liquid in said tank.

3. In a liquid rheostat, the combination 50 with a tank for containing fluid, and having a discharge opening, of a stationary tubular member associated with said discharge opening and having apertures therein in near its lower end, a longitudinally movable tubular member surrounding the lower end of said first member and adapted to cover said apertures, and a longitudinally movable tubular member disposed within said first member for fixing the height of 60 the fluid.

4. The combination with a liquid-containing tank having a bottom discharge opening, of a tubular member fixed to the edge of said opening and projecting upwardly 65 into said tank and having side apertures near its lower end, a relatively short tubular member surrounding the lower end of said first tubular member and adapted to cover said apertures, a relatively long tubular member disposed within said first member and separate means associated with said second and said third members for independently raising and lowering said members in position.

5. The combination with a liquid-containing tank having a discharge opening, of a stationary tubular member, a movable member located within said stationary member and adapted to maintain the liquid level 80 substantially flush with its own upper end, and a second member surrounding said stationary member and movable in the same directions as said first movable member for controlling the discharge of liquid through 85 said opening.

In testimony whereof, I have hereunto subscribed my name this 30th day of March 1914.

GEORGE M. EATON.
